UNITED STATES PATENT OFFICE.

JOHN F. O'CONNOR, OF CHICAGO, ILLINOIS, ASSIGNOR TO WILLIAM H. MINER, OF CHICAGO, ILLINOIS.

DRAFT-RIGGING FOR RAILWAY-CARS.

1,136,039.

Specification of Letters Patent. Patented Apr. 20, 1915.

Application filed April 11, 1914. Serial No. 831,285.

To all whom it may concern:

Be it known that I, JOHN F. O'CONNOR, a citizen of the United States, residing at Chicago, in the county of Cook and State of Illinois, have invented a certain new and useful Improvement in Draft-Rigging for Railway-Cars, of which the following is a full, clear, concise, and exact description, reference being had to the accompanying drawings, forming a part of this specification.

My invention relates to draft rigging for railway cars.

The object of my invention is, to provide a draft rigging of efficient operation.

In the drawings forming a part of this specification Figure 1 is a side elevation, partly in vertical longitudinal section, of a draft rigging embodying my invention, and showing the parts in normal position; Fig. 2 is a plan view partly in horizontal section on line 2—2 of Fig. 1, and showing the spring elements compressed in draft; Fig. 3 is a plan view, partly in horizontal section, 25 showing the position of the parts when in full buff; Fig. 4 is a cross section taken on line 4—4 of Fig. 1; Fig. 5 is a rear end view of the shell; Fig. 6 is a detail view illustrating the rear follower; Fig. 7 illustrates a 30 modification.

Referring to the drawings, the numerals 8—8 indicate draft members or parts of the car-frame to which the draft rigging is applied; 9 a draw-bar, only the rear end thereof being shown in the drawings; 10 a draft-yoke slidably keyed to the draw-bar, preferably comprising a U-shaped yoke-strap 11 provided at its free ends with a hollow box-like member 12 having lateral slots 13 to receive the coupler-key 14. The coupler-key extends through the draw-bar and said slots, and through slots 15 provided in adjacent portions of the draft members. The slots 15 are longitudinally extended to permit reciprocating movement of the key therein. The slots 13 of the yoke are rearwardly extended to permit the rearward movement of the draw-bar without buffing strain upon the key 14. A draft-gear 16 is mounted between the draft members, the draft-gear comprising a shell 17 open at both ends, and preferably being a hollow cylinder in form. Friction elements 18 and spring elements 19 are mounted within the shell, the friction elements preferably comprising a plurality of

friction shoes 20, a wedge 21, and anti-friction rollers 22 interposed between each friction shoe and the adjacent wedging faces of the wedge. The spring elements preferably comprise an outer spring 23 and an inner spring 24 nested therein, the said springs being seated at their forward ends against the friction elements. Rearwardly the spring elements are seated against a follower 25. At its rear end the shell is provided with a preferably vertical slot or recess adapted to permit the reciprocating movement of the rear follower 25 therein, and adapted to permit the entry therein of the vertical filler-block 26 with which the yoke is provided at its rear end. The rear follower 25 is adapted to enter the rear portion of the shell, and is provided with upwardly and downwardly extending flanges 27 adapted to engage against the rear shoulders 28 with which the shell is provided to limit the inward movement of the follower in the shell. In preferable construction, the rear follower is provided with transverse slots 29—29, each adapted for the passage of a supporting bar or rivet 30, each supporting member 30 being secured at its ends in the shell. A connecting rod 32 connects the friction elements with the rear follower and limits the separating movement of the same, the head 33 of the said rod being received in a recess 34 of the wedge, and the nut 35 thereof being received in a recess 36 in the rear face of the rear follower 25. A tie-plate 37 secured to the draft member is adapted to support the draft-gear. Stop-members 38—38 are secured to the inner faces of the draft-members, the stop-members being provided with front stop-shoulders 39, front limiting stop-shoulders 40, rear stop-shoulders 41—41, 95 and shoulders 42—42 in front of the rear stop-shoulders 41, forming a space 43—43 in either stop-member, the said spaces being adapted to receive the outwardly projecting shoulders 44—44 with which the shell is laterally provided at its rear end, the said shoulders being preferably integral with the shell, and being preferably arranged at either side of the vertical recess in the rear end of the shell. The front follower is indicated by the numeral 46, the same being in engagement with the friction elements within the shell and performing its usual function. It will be observed that the shell is rigidly mounted between the draft mem- 110

bers, that is, the same is secured therein against longitudinal movement.

On rearward movement of the draw-bar, the same forces the front follower rearwardly, bringing the friction elements within the shell into resisting action, the inward movement of the friction elements being resisted by the spring elements, the spring elements being stopped against rearward movement by the rear follower, the rear follower being held against rearward movement by the transverse members 30 engaging against the forward ends of the slots 29 through the rear follower, and the shell 15 being stopped against rearward movement through engagement of the lateral shoulders thereof within the recesses 43 in the stop members. Thus in rearward movement of the draw-bar, both the friction elements and spring elements of the draft-gear are brought into compression resisting action.

On forward movement of the draw-bar, the yoke is drawn forwardly, the rear end 25 of the yoke operating in the vertical recess of the rear end of the shell and drawing the rear follower forwardly, compressing the spring elements against the friction elements, the friction elements being stopped 30 by the front follower, which in turn is held against forward movement by the front stop-shoulders 39. In forward movement of the draw-bar, the shell is also stationary, and the friction elements are not brought 35 into frictional resisting action.

In the modification illustrated in Fig. 7 of the drawings, the numerals 60—60 indicate draft members or parts of the car-frame to which the draft rigging is applied; 61 40 the draw-bar, only the rear end thereof being shown; 62 the draft-yoke connected to the draw-bar; 64 the front follower; 65—65 stop members having front stop-shoulders 66—66, front limiting stop-shoulders 45 67—67, rear stop-shoulders 68—68, and rear limiting stop-shoulders 69—69. The draft-gear 70 comprises the shell 71, open at both ends, containing the frictional elements 72 and the spring elements 73, the spring elements being seated at their forward ends against the friction elements, and being rearwardly seated against the rear follower 74. The rear follower and friction elements are limited in their separating movement by 55 the connecting bolt 75 engaging the wedge 76 at one end and the rear follower 74 at the other end. At its rear end the shell is provided with a vertical recess 77 adapted to permit the entry of the rear end 78 of 60 the draft-yoke 62, the rear follower being mounted upon transverse members 79 extending through slots 80 in said rear follower, the said slots 80 being longitudinally extended to permit the forward movement 65 of the follower upon the said transverse

member 79. At its rear end the shell is provided with laterally extended shoulders 81—81, which are preferably integral with the shell and are adapted to enter the space in the stop members between the rear stop-shoulders 68 and the rear limiting stop-shoulders 69. In this modification, a preferably slight longitudinal movement of the shell is provided for in that the said shoulders 81 are of lesser length than the length 75 of the slots in the stop members in which they are received. This provision for slight longitudinal movement of the shell is the difference in structure between the preferred embodiment of my invention as illustrated 80 in Figs. 1 to 6, inclusive, of the drawings, and the modification shown in Fig. 7. In the structure illustrated in Fig. 7 of the drawings, on rearward movement of the draw-bar, the front follower 64 is forced 85 rearwardly, its rearward movement being resisted by the action of the friction elements and spring elements within the shell, the springs being held against rearward movement by the transverse member 79 passing through the rear follower and the shell, and the shell being held against rearward movement through its engagement against the rear stop-shoulders 68.

On forward movement of the draw-bar, 95 the rear follower is drawn forwardly by the yoke, the rear end of which operates in the vertical recess rearwardly provided in the shell, compressing the springs against the friction elements until the rear follower engages the rear end of the shell, whereupon the shell is drawn forwardly until the shoulders at the rear end thereof engage the rear limiting stop-shoulders 69, the friction elements within the shell being in frictional 100 action with the shell during the forward movement thereof. Thus on forward movement of the draw-bar, the initial compression-resisting elements employed are the spring elements, and near the end of the forward movement, both the spring elements and friction elements are in compression resisting action.

I claim:

1. In a draft rigging for railway cars, in 115 combination, draft members, a shell secured against longitudinal movement between the draft members, friction elements and spring elements within the shell, a rear follower engaging the compression resisting elements 120 within the shell, the shell being rearwardly provided with a recess for the entry of the draft yoke on forward movement thereof, the draft yoke being in engagement with the rear follower.

2. In a draft rigging for railway cars, in 125 combination, draft members, a draw-bar, a yoke connected to the draw-bar, a shell open at both ends and secured against longitudinal movement between the draft members,

compression resisting elements within the shell, a rear follower adapted to enter the shell and to be engaged by the draft yoke, the shell being rearwardly provided with a recess to receive the end of the draft yoke in its forward movement.

3. In a draft rigging for railway cars, in combination, draft members, a draw-bar, a draft yoke, a shell open at its ends, friction elements and spring elements within the shell, a follower engaging the spring elements and slidingly operating in the shell, stop members, the shell being provided with shoulders, and the stop members being provided with slots to receive said shoulders to hold the shell against longitudinal movement, the draft yoke engaging the follower on forward movement of the draw-bar, and compressing the spring elements against the friction elements without frictional movement of said friction elements, said follower serving as an abutment for the spring ele-

ments upon rearward movement of the draw-bar whereby both the friction elements and the spring elements are brought into play 25 upon rearward movement of the draw-bar.

4. In a draft rigging for railway cars, in combination, draft members, draw-bar, a yoke secured thereto, a shell, friction elements and spring elements within the shell, 30 stop members and followers, the shell being provided with outwardly extended shoulders, the stop members having recesses to receive said shoulders to secure the shell against longitudinal movement, one of the 35 followers entering one end of the shell and engaging the spring elements, the said follower being provided with means passing through the shell to limit the outward movement of said follower.

JOHN F. O'CONNOR.
